HARRY M. SCOTT, OF CHICKASHA, OKLAHOMA, ASSIGNOR, BY MESNE ASSIGNMENTS, TO
SCOTT PATENTS CORPORATION, OF CHICAGO, ILLINOIS, A CORPORATION OF ILLINOIS

METHOD AND DEVICE FOR INSERTING PADDING INTO UPHOLSTERY

Application filed June 7, 1928. Serial No. 283,659.

This invention relates to a method and a device for inserting padding into piping for forming cushions or upholstery.

An object of the invention is the provision of a device for distending a plurality of pipings and for forcing and packing the padding into the piping through an alternate reciprocation of a plurality of toothed plates.

Another object of the invention is the provision of a method of packing padding into a plurality of connected pipings by distending the piping in line with a confined space through which the padding is fed, while advancing the padding at diametrically opposite site points, and in an alternate relation.

A further object of the invention is the provision of a device for inserting and packing padding strips into piping in which a plurality of plates are operated in pairs with one plate being moved in one direction, while a coordinate plate of a pair is moved in the opposite direction, said plates being located on opposite sides respectively of the padding strip, teeth being provided on the plates and having their free ends extending towards the direction of movement of the plates for engaging and forcing the padding forwardly into the piping, while being released from the padding upon the return stroke so that at all times some part of the padding is being moved into packed relation in the piping and being fed in a continuous stream to the reciprocating plates.

This invention will be best understood from a consideration of the following detailed description in connection with the accompanying drawings; nevertheless, it is to be understood that the invention is not confined to the disclosure being susceptible of such changes and modifications as shall define no material departure from the salient features of the invention as expressed in the appended claims.

In the drawings:—

Figure 1 is a plan view of a device for inserting padding into piping and constructed according to the principles of my invention,

Figure 2 is one side view of the same,

Figure 3 is an opposite side view of the device,

Figure 4 is a longitudinal section of the padding inserting device,

Figure 5 is a transverse vertical section taken along the line 5—5 of Fig. 4.

Figure 6 is a transverse vertical section 55 taken on the line 6—6 of Fig. 4.

Referring more particularly to the drawings 10 and 11 designate legs of angle iron construction for supporting a frame work of the device for inserting padding into pipings. 60 Side plates 12 and 13 are supported by the legs and connected together by transverse members 14, 15 and 16.

A plurality of tubes 20 for receiving the piping which is adapted to be filled with 65 padding, are located in a horizontal plane and are supported by the spaced parallel transverse plates 14. These tubes extend longitudinally of the frame and project outwardly from the discharge end of the device. 70 The tubes terminate at 21 with their inner ends adjacent the inner ends of the feeding tubes 22. The tubes 22 are located in alignment with the tubes 20. It will be noted that the feeding tubes are of smaller cross sectional area than the tubes 20 and are located between pairs of slidably mounted feeding bars 23 and 24. Spacing bars 25 are located between each pair of feeding tubes 22.

The reciprocating plates 23 and 24 are engaged upon opposite sides of the feeding tubes 22. These plates have teeth 30 extending from their adjacent faces in a direction which is toward the outer end of the tubes 20 so that when the plates are moved forwardly the teeth will engage the padding and force the same outwardly, while the teeth are released during the return stroke of the plates. The outer ends of these plates are supported in spaced relation by the padding 80 which is being forced into the piping from the open ends 31 of the tubes 20.

Each of the plates 23 is provided with a pair of spaced ears 32 having vertical slots 33 to receive pins 34 carried by the lower end 95 of an oscillating arm 35. The arms 35 are pivotally mounted on a rod 36 extending between the opposite sides of the machine and supported in brackets 37 secured to the side plates 12 and 13. A rod 38 extends through 100

several oscillating arms 35 for connecting said arms together for simultaneous oscillating movement. A pair of pitmen 40 are pivotally connected at one end to the rod 38 and at the other end are pivoted on a rod 42 extending between a pair of crank arms 41, which latter are fast on a pair of alined stub shafts 43 journaled in the side walls 12 and 13.

A similar mechanism is employed for reciprocating the lower plate 24, the same consisting of ears 55 attached to the under side of each plate and formed with vertical slots 54 to receive a pin 53 in the upper end of an arm 45 pivoted on a transverse rod 46 mounted in brackets 47 attached to the side plates 12 and 13. Through the several arms 45 extends a rod 48 to which is connected one end of a pair of pitmen 49, said pitmen being pivoted at the other end on a transverse rod 50 mounted in and between a pair of crank arms 51 that are fast on stub shafts 52 journaled in the side plates 12 and 13.

Referring more particularly to Figs. 2 and 3 it will be seen that a system of sprockets and chains is employed for rotating the shafts 43 and 52 from a drive shaft 60. On one side of the device a sprocket chain 61 is trained over sprocket wheels 62 and 63 on the shafts 43 and 52 respectively and over a driving sprocket 64 on the drive shaft 60, the chain being maintained taut by an idler sprocket 65. On the other side a similar chain 61^a is trained over sprockets 62^a and 63^a on the shafts 43 and 52 respectively and over a drive sprocket 64^a on the drive shaft 60, being kept taut by an idler sprocket 65^a.

An upper peripherally toothed feed roll 71 is formed with end pintles 70 journaled in the side plates 12 and 13 and is driven from one of the shafts 43 by a sprocket wheel 74 fast on shaft 43, a sprocket chain 78^a, and a sprocket wheel 72 fast on one of the feed roll pintles 70. The lower peripherally toothed feed roll 75 is formed with end pintles 76 journaled in the frame plates 12 and 13 and is driven from one of the shafts 52 by a sprocket 79 fast on shaft 52, a sprocket chain 78, and a sprocket wheel 77 fast on pintle 76, the chain 78 being trained over an idler sprocket 80 journaled on an extension of the frame plate 12. It will be noted by reference to Fig. 4 that the feed rolls 71 and 75 are located in spaced relation adjacent to the outer end of the feeding tubes 22, the space between said rolls being substantially in line with the axes of said tubes. In front of the feed rolls 71 and 75 are mounted two series of alternating feed chutes 83 and 84, for the padding; the upper series 83 being downwardly inclined toward the feed rolls and the lower series 84 upwardly inclined toward the feed rolls. Lips 85 and 86 are provided at the outer ends of the chutes 83 and 84 for properly directing the padding into said chutes. By reason of the V-shaped form of the chutes, converg-

ing toward the feed rolls, the outer wide ends receive the padding, and the latter is gradually compressed or reduced in width, and correspondingly increased in thickness, as it reaches and is forced by the rolls into the feeding tubes 22.

The operation of my device is as follows: A piping 100 is formed of some suitable fabric and is arranged in parallel series and slipped over the horizontally disposed tubes 20, shown in Fig. 2. The padding is placed in the guides 83 and 84, and the free ends are inserted between the rolls 71 and 75. Power is applied through the shaft 60 and the chains and sprockets cause oscillation of the arms 35 and 45 and likewise the reciprocating plates 23 and 24. The padding having been reduced in cross sectional area by the inner ends of the guides 83 and 84 is fed by the rolls 71 and 75 into the feeding tubes 22. After the padding projects from the inner end of the tubes 22, it is engaged by the teeth 30 of the reciprocating plates 23 and 24 which move the padding along, and pack it against the closed end 101 of the piping 100. As the padding is packed and forced against the closed end, the filled piping is progressively moved from the tubes while being filled. It will be noted that the plates 23 and 24 move in opposite directions in alternating relation so that while the plate 23 is moving outwardly, the plate 24 is being returned. By this means the padding is moved forwardly along its upper edge by the plate 23 after which it is moved along its lower edge by the plate 24. It will be seen by this construction that the operation of inserting the padding into the piping is not only continuous, but an even distribution of the padding is had by the alternate reciprocations of the plates 23 and 24.

I claim:

1. Apparatus for inserting padding into upholstery piping, comprising a plurality of open-ended fixed tubes disposed in spaced relation in a common plane and adapted to extend throughout the lengths of and distend the individual pipes of the upholstery material, means for feeding a plurality of substantially continuous strips of padding material to the inlet ends of the tubes and simultaneously comprising said strips and reciprocating feeders in the tubes on opposite sides respectively of the strips for forcing the latter therethrough into the piping and for simultaneously removing the piping from the tubes, substantially as described.

2. Apparatus for inserting padding into pipes of upholstery material comprising a plurality of open-ended fixed tubes disposed in spaced relation in a common plane and flattened in a direction at right angles to such plane, said tubes being adapted to extend throughout the lengths of and to distend the individual pipes of the upholstery

material, means for guiding a plurality of substantially continuous strips of padding material to the inlet ends of the tubes, and reciprocating feeding plates having inclined teeth in the tubes on opposite sides respectively of the strips for forcing the latter therethrough and into the piping and for simultaneously removing the piping from the tubes, substantially as described.

3. Apparatus for inserting padding into pipes of upholstery material comprising a plurality of open-ended fixed tubes disposed in spaced relation in a common plane and flattened in a direction at right angles to such plane, said tubes being adapted to extend throughout the lengths of and to distend the individual pipes of the upholstery material, means for guiding a plurality of substantially continuous strips of padding material to the inlet ends of the tubes, and reciprocating feeding plates having inclined teeth in the tubes for forcing the material therethrough and into the piping and for simultaneously removing the piping from the tubes, said feeding plates being substantially co-extensive with the width of the tubes and engaging opposed walls thereof, substantially as described.

4. Apparatus for inserting padding into the pipes of upholstery material, comprising a plurality of open-ended fixed tubes disposed in spaced relation in a common plane and adapted to extend throughout the lengths of and distend the individual pipes of the upholstery material, means for guiding a plurality of substantially continuous strips of padding material to the inlet ends of the tubes, reciprocating feeders extending through the tubes for forcing the strips therethrough and into the piping and for simultaneously removing the piping from the tubes, and mechanism disposed out of alignment with the tubes for reciprocating said feeders, substantially as described.

5. Apparatus for inserting padding into the pipes of upholstery material, comprising a plurality of open-ended fixed tubes disposed in spaced relation in a common plane and adapted to extend throughout the lengths of and distend the individual pipes of the upholstery material, means disposed substantially in alignment with the tubes for feeding a plurality of substantially continuous strips of padding material to the inlet ends thereof, reciprocating feeders in the tubes for forcing the material therethrough and into the piping as the piping is removed from the tubes, and mechanism out of alignment with the tubes for reciprocating the feeders, substantially as described.

6. Apparatus for inserting padding into piping comprising a plurality of tubes to receive and retain the piping in distended relation, reciprocating plates provided with teeth and movable in the tubes for forcing the

padding into the piping, means for compacting and feeding the padding to the reciprocating plates, means for causing reciprocation of the plates, the tubes being located in a plane, the feeding means being so arranged as to cause the padding to be fed to alternate tubes from opposite sides of the plane passing through the tubes.

7. The method of inserting padding into the pipes of upholstery material which comprises disposing the material in a common plane and distending the individual pipes throughout the full lengths thereof, compressing and feeding a plurality of strips of padding material into confined spaces co-extensive with the distended pipes, and then simultaneously forcing the compacted strips into the individual pipes of upholstery material and advancing the material as the individual pipes thereof are stuffed, substantially as described.

8. Apparatus for inserting substantially continuous strips of padding into piping, comprising a plurality of fixed tubes to receive and retain the piping in distended relation, a pair of toothed plates movable in each of the tubes on opposite sides respectively of the padding strips for forcing the latter into the piping, means for feeding and guiding the strips between said plates, and means for moving one of the plates forwardly and for simultaneously moving the other plate backwardly.

9. Apparatus for inserting substantially continuous strips of padding into piping, comprising a plurality of fixed tubes to receive and retain the piping in distended relation, a pair of toothed plates movable in each of the tubes on opposite sides respectively of the padding strips for forcing the latter into the piping, means for feeding the strips, means for causing simultaneous reciprocation of said plates in opposite directions, and a tube having an end located adjacent to the feeding means for receiving and guiding the strips between the plates.

10. Apparatus for inserting substantially continuous strips of padding into piping, comprising a plurality of fixed tubes to receive and retain the piping in distended relation, a pair of toothed plates movable in each of the tubes respectively above and below the padding strips for forcing the latter into the piping, means for feeding and guiding the strips between said plates, and means for moving one of the plates forwardly and for simultaneously moving the other plate backwardly; the teeth being located at an acute angle to the plates and upon the adjacent surfaces of the latter, and the free ends of said teeth being directed towards the outer ends of the tubes so that the teeth will engage the strips and force the same forwardly upon the forward strokes of the

plates, but will remain inactive on the strips during the return strokes of the plates.

11. In a stuffing machine for upholstery piping, a plurality of tubes over which the piping is drawn, means for guiding, compressing and feeding a plurality of strips to said tubes including a pair of feed rolls and a series of guide chutes extending into the inlet ends of said tubes, and reciprocating feeders in said tubes for advancing the strips therethrough.

12. In a stuffing machine for upholstery piping, a plurality of tubes over which the piping is drawn, means for guiding, compressing and feeding a plurality of strips to said tubes including a pair of feed rolls and a series of guide chutes extending into the inlet ends of said tubes, and toothed reciprocating feed plates extending substantially throughout the length of said tubes and between the walls thereof and the walls of said guide chutes.

13. In a stuffing machine for upholstery piping, a plurality of open-ended but otherwise closed tubes arranged side by side and over which the piping is drawn, means for compressing, guiding and feeding a plurality of substantially continuous stuffing strips to said tubes, and reciprocating toothed feeding plates extending substantially throughout the lengths of said tubes for advancing the stuffing strips therethrough.

CERTIFICATE OF CORRECTION.

Patent No. 1,842,845.

Granted January 26, 1932, to

HARRY M. SCOTT.

It is hereby certified that error appears in the printed specification of the above numbered patent requiring correction as follows: Page 2, line 117, claim 1, for the word "comprising" read compressing; page 3, line 90, claim 8, for "distending" read distended; and that the said Letters Patent should be read with these corrections therein that the same may conform to the record of the case in the Patent Office.

Signed and sealed this 1st day of March, A. D. 1932.
